BILLFOLD

Joseph C. Miller, Compton, Calif., assignor to
 Coast Envelope & Leather Products Company,
 a corporation of California

Application January 24, 1944, Serial No. 519,487

2 Claims. (Cl. 150—38)

1

This invention relates to an improved billfold formed of flexible material of the type used to carry bills, cards and the like.

An object of this invention is to provide a billfold of the character referred to of simple form and construction, consisting of a single blank which when folded provides a substantially flat money and card receptacle.

Another object of my invention is to provide a billfold of simple form and construction in which the outer and inner wall are secured together at their longitudinal edges so that there is no relative movement therebetween and the remainder of the members constituting the billfold being so connected to each other and to the outer and inner walls directly along the longitudinal folding edges in such a manner that there is no relative independent movement therebetween.

Other objects and advantages will appear from the following description and drawings. Referring to the drawings, which are for illustrative purposes only,

Fig. 1 is a blank of flexible material from which the billfold is made;

Fig. 2 is a view similar to Fig. 1 after the first folding operation has been performed;

Fig. 3 is a view similar to Fig. 2 after the second folding operation has been performed;

Fig. 4 is a view of the completed billfold looking toward the inner wall;

Fig. 5 is a face view of the divider;

Fig. 6 is a sectional, perspective view along lines 6—6 of Fig. 4;

Fig. 7 is an enlarged sectional view on line 7—7 of Fig. 2 showing the manner of connecting the divider to the bridging member; and

Fig. 8 is an enlarged sectional view on line 8—8 of Fig. 4.

Referring more particularly to the drawings, in Fig. 1 is shown a blank generally indicated at 10. This blank, as heretofore indicated, is made of flexible material and may be considered as divided by three folding lines indicated by dot-dash lines indicated at 11, 12 and 13 into four parts generally referred to as an outer wall 15, an inner wall 16, a connecting wall 17 and a bridging member or wall 18. While I have shown the blank 10 as made of a single piece of flexible material it is to be understood that the blank may be made of two pieces, one piece forming the outer and inner walls 15 and 16 and the other part forming the connecting wall 17 and bridging member or wall 18. When so made the two parts may be sewed or otherwise secured to each other at or adjacent to the folding line 12.

2

The purpose of making the blank in two parts is that more expensive or better finished material may be used for the exposed parts of the billfold while the parts forming the connecting wall and bridging member may be made of lighter material which is more easily folded and produces a flatter billfold.

The blank 10 is cut out forming an opening indicated at 20 which extends from the folding line 11 to the folding line 13, a tongue 21 being left attached to the wall 15, which tongue is folded back upon the inner face of the wall 15 as shown in Fig. 2 and cemented or otherwise secured to such wall 15 thereby doing away with what might otherwise be a raw edge on the wall 15 at the end of the opening 20. The opening 20 divides the inner wall 16 into two parts or wall members 16' and the connecting wall 17 into two parts or wall members 17'.

For the purpose of making a finished edge along the side of the wall 15, the exposed edge 22 of such wall 15 is folded inwardly and downwardly on the wall 15 and secured thereto by cementing, this edge being folded on the dot-dash line 23.

The wall 15 is provided at each end with a flap 24 by means of which the ends of the walls 15 and 16 are secured together as hereinafter described.

30 The billfold may be made with or without a divider wall for separating bills or other papers in the billfold. When the divider is included notches, indicated at 26, are cut in the ends of wall 17 and corresponding tabs 27 formed in the ends of the bridging member 18 by cutting such member in from the ends. The divider is a single flat member 30 of flexible material as shown in Fig. 5.

The blank heretofore described is folded into 40 a billfold in the following manner: The first operation is to fold the bridging member 18 on the connecting wall 17 and when so folded the blank has the appearance shown in Fig. 2. The divider wall 30 is then placed under the connecting wall 17 as shown in dotted lines in Fig. 2 and such wall is sewed to the tabs 27 of the wall 18 as shown in Fig. 7, the sewing being indicated at 45 31. The superimposed walls 17 and 18 together with the divider wall 30 are then folded as a unit 50 on the inner wall 16 assuming the position shown in Fig. 3. When this has been done the flaps 24 on the outer wall 15 are folded inwardly as shown in Fig. 3 and cement is applied to the face of such flaps and on the end margins 33 of the 55 inner wall 16. When this has been done the

superimposed walls 16, 17 and 18 together with the divider wall 30 are folded as a unit so that the cemented flaps 24 and the margins 33 of the wall 16 engage each other and are cemented together after which the billfold is completed and has the appearance shown in Fig. 4. The notches 26 receive the stitched tabs 27, thereby preventing the over-all thickness of the device being increased by the stitching. Such mounting of the divider wall is also conducive to flexibility and to accessibility of the bottoms of the billfold compartments.

The connecting wall 17 and bridging member or wall 18 are shorter in length than the inner and outer walls so that when the ends of the inner wall and the flaps 24 are cemented together the pocket so formed by the inner and outer wall freely receives the ends of the bridging member and connecting wall. This difference in length in the walls results in the forming of shoulders 40 at the upper corners of the inner wall 16.

At the upper edge corners of the billfold at the point where the flaps 24 are cemented to the upper end edges of the wall 16, that is, at the shoulders 40 there is a tendency for such parts to become loosened or torn after continued use of the billfold. To obviate this I use a U-shaped metal member indicated at 35 which extends over the upper edge of the flaps 24 and the upper corners of the wall 16, the legs of this U-shaped clamping member are then pressed together firmly clamping the parts together and protecting such corners of the billfold.

When the billfold is made without the divider it is to be understood that the wall 17 is not notched nor the wall 18 provided with tabs as heretofore described but that the billfold then is made from the blank by simply performing the folding operations heretofore described and the ends of the inner and outer walls are cemented together.

The billfold as shown in Fig. 4 is as it appears when access is desired to the contents of the billfold but when carried the billfold is merely folded in half, that is, one side upon the other. A billfold made as herein described is less costly to manufacture than the ordinary billfolds of this character and may be folded as just referred to without buckling of the parts or forming a bulky article.

Although the invention has been particularly shown and described it is contemplated that various modifications and changes can be made without departing from the scope of the invention and it is intended to cover such changes as come within the claims.

I claim as my invention:

1. A billfold comprising: outer and inner walls

of flexible material, said outer wall being rectangular in shape and having an area inclusive of the area of a bill to be carried, said inner wall being formed of two spaced inner wall members each forming an extension of the outer wall member; a bridging member of rectangular shape; a two part connecting wall member attached along one edge to the inner wall and along the opposite edge to the bridging member, all of said members forming one continuous flexible blank and said bridging member, said connecting wall and said inner wall being successively folded upon each other and upon the outer wall; means for permanently securing the end edges of the outer wall to the end edges of the inner wall; and a divider member between the outer wall and the connecting wall attached at its ends to the bridging member.

2. A billfold comprising: outer and inner walls of flexible material, said outer wall being rectangular in shape and having an area inclusive of the area of a bill to be carried, said inner wall being formed of two spaced inner wall members each forming an extension of the outer wall member; a bridging member of rectangular shape; a two part connecting wall member attached along one edge to the inner wall and along the opposite edge to the bridging member, all of said members forming one continuous flexible blank and said bridging member, said connecting wall and said inner wall being successively folded upon each other and upon the outer wall; means for permanently securing the end edges of the outer wall to the end edges of the inner wall, said connecting wall having a notch at each end; tabs on said bridging member corresponding to the notches in the connecting wall; and a divider member between the outer wall and connecting wall secured at each end to the tabs on the bridging member.
